UNITED STATES PATENT OFFICE.

FRANK H. NEWTON, OF LOS ANGELES, CALIFORNIA.

SHOE-SHINING MACHINE.

Application filed October 13, 1924. Serial No. 743,373.

This invention relates to and has for a main object the provision of an improved type of shoe shining machine of the general character of the device shown in my pending application for patent filed June 21, 1923; Serial Number 646,762, and embodying numerous improvements over the form of device shown in said application for patent.

10 The principal object of the present invention is to provide in a machine having a plurality of sets of brushes adapted to be rotatably and reciprocably mounted for contact with the shoes of means for continuously reciprocating all of said brushes together for a given period of time and for rotating said brushes correspondingly for a fraction of a revolution at given intervals during the reciprocation thereof, for rendering certain 15 brushes operative and certain others inoperative.

20 Another object is to provide a plurality of sets of brushes, each set including a plurality of units and each unit including separate brushes or elements for cleaning, polishing and shining the shoes in the order named, together with means for reciprocating all of said brushes for a given period of time and for rotatably moving said brushes into operative position in the order of their use.

A further object is to provide improved means for applying the polish to the brushes and embodying compressed air means for spraying polish on the brushes preparatory 35 to the application of the polish to the shoes.

Numerous other improvements will be noted during the progress of the description hereinafter following.

I have shown in the accompanying drawings a preferred embodiment of my invention, subject to modification within the scope of the appended claims without departing from the spirit thereof.

In said drawings:

45 Fig. 1 is a perspective external view of the machine.

Fig. 2 is a top plan view of the machine in which the housing is shown in section.

50 Fig. 3 is a sectional plan of the driving mechanism on line 3—3 of Fig. 7.

Fig. 4 is a sectional plan of the same on line 4—4 of Fig. 7.

Fig. 5 is a face view of the intermittent driving mechanism for rotating the brushes.

55 Fig. 6 is a perspective view of the driven gear, shown in Fig. 5.

Fig. 7 is a longitudinal sectional elevation on line 7—7 of Fig. 2.

Fig. 7^a is a plan view in detail of the control operating yoke. 60

Fig. 8 is a substantially enlarged sectional elevation of the machine on line 8—8 of Fig. 2.

Fig. 9 is a rear elevation of the machine on line 9—9 of Fig. 2. 65

Fig. 10 is a plan view of one of the brush sets for engagement with the sides of the shoes.

Fig. 11 is an elevation of the same, partly in section. 70

Fig. 12 is a section of the same on line 12—12 of Fig. 10.

Fig. 13 is a fragmentary section of the same on line 13—13 of Fig. 11.

Fig. 14 is an enlarged side elevation of 75 the coin controlled starting and stopping mechanism.

Fig. 15 is a sectional elevation of the switch box shown in Fig. 14, and forming a part of the starting and stopping mechanism. 80

Fig. 16 is a transverse sectional elevation of the same on line 16—16 of Fig. 15.

Fig. 17 is a continuation of Fig. 16 showing the connection of the switch box with the 85 driving mechanism whereby the switch is operated for stopping the machine after a complete operation.

Fig. 18 is a fragmentary view, partly in section, of the coin operated starting mechanism. 90

Fig. 19 is a sectional elevation of one of the spray devices for applying the polish to the brushes.

Fig. 20 is a fragmentary plan view of the 95 spray operating mechanism; and

Fig. 21 is an elevation of the same partly in section.

Fig. 22 is a plan of the control and timing mechanism. 100

Referring to Fig. 1 my machine embodies a housing H formed of wood or sheet metal and adapted to completely enclose all of the operating parts of the machine against unauthorized access.

The housing has sides 1, 1, a front end 2, a rear end 3, a top 4 and a seat 5 which may be upholstered as shown and elevated above the flat top 4 of the housing for a suitable distance. The rear portion of the housing 110 is substantially higher than the front portion thereof and has portions 6—6 at each

side of the seat which may form arm rests for the seat. The entire housing may be reinforced at the edges and corners by means of suitable angle irons as at 7, 7, or otherwise, this being immaterial to my invention. The flat top portion 4 of the housing is provided with openings 8, 8 in front of the seat 5 and substantially spaced apart for receiving the feet of an occupant of the seat during a shoe shining operation, as more fully explained hereinafter.

The entire mechanism is adapted to be mounted on a rigid bed plate P of cast metal, to which the housing 8 is attached by suitable means and on the upper side of this bed plate I provide a pair of like frame members F and F' which are secured to and are fixedly held on the floor 10 of the bed plate P by means of bolts 11, 11, etc., which extend through the feet 12 of said frames.

As shown in Fig. 2 particularly, the frames F and F' are connected longitudinally of the base by means of a plurality of rods r, r, etc., the ends of said rods being held in bearings in said frames by means of set screws 13, 13, etc. Said frames are also additionally connected by means of a plurality of shafts r', r', etc., which are journaled in bearings in said frames F and F', and are adapted to be operatively connected together at the rear of the frame member F' by means of a train of gears shown in Fig. 2.

Each of the shafts r' has a gear g fixed to the rear end thereof, as shown in Figs. 2 and 9, and all of the gears on said shafts r', r', etc., are operatively connected with a central gear g' by means of a series of gears 15, 16, 17, 18, 19, 20, 21, 22, 23 and 24, as shown in Fig. 9, and as seen therein from left to right in the figure of the drawing.

All of said gears are rotatably mounted on the frame member F' and are so arranged that the shafts r' will be rotated to the same extent and at the same speed when said gears are rotated.

The central gear g' is rotatably mounted on a bushing 25 which is held in a central boss 26 of the frame F', as shown in Fig. 7, and said bushing forms a bearing for a hollow shaft S which is adapted to be reciprocably mounted in the frame member F' and supported for movement on a central elongated rod R which is fixedly held at the front end thereof in a bearing 27 of frame member F, and at its rear end in a bearing 28 of a frame member F'' which is also supported on and fixed to the bed plate P, as shown in Fig. 7. Frames F' and F'' are also connected by a rod R'.

Now, it will be understood that the shafts r' are adapted to be rotated at intervals for a fraction of a revolution, and the shaft S is adapted to be reciprocated continuously during the operation of the machine, and to

this end I have provided a suitable driving mechanism as shown in Figs. 3, 4, 5, 6 and 7 which I will now describe with reference to said figures.

A motor M is provided at the rear of the machine and is suitably mounted on the bed plate P. Said motor is adapted to be connected by means of a suitable coupling device C with a drive shaft D which is journaled in bearings d, d, in a gear housing composed of members h and h' which are bolted together by means of a plurality of bolts 29, 29, etc., said gear housing being positioned in the longitudinal center of the machine in the transverse plane of the motor M, and the lower housing member h' being suitably attached to the bed plate B.

The drive shaft D carries a worm W intermediate the bearings d, d, which meshes with and drives a worm gear G supported on a vertically driven shaft D' in the housing members h and h'. Below the plane of the gear G a gear 30 is provided in the housing member h' which is fixed to the shaft D' and drives a similar gear 31 by means of an idler 32 interposed therebetween, said idler being mounted on a shaft 33 and the gear 31 being fixed to a vertical shaft 34.

The inner portion of the housing member h has an auxiliary housing portion h'' which encloses a reducing worm W' adapted to mesh with and drive a worm gear G', said worm W' and said gear G' being enclosed in the housing portion h'' and the gear G' being mounted on a horizontal shaft 35 which extends through and has a bearing in the frame member F' and carries on its inner end an intermittent driving gear I, as shown in Figs. 4 and 5, which is adapted to mesh with and drive a pinion I'.

Said pinion is mounted on a shaft 36 which is journaled in the frame F', and a spur gear 37 is provided on the rear side of the frame F' and fixed to the shaft 36, which in turn meshes with an idler 38 which serves to operatively connect the gear 37 with the central gear g' carried on the bushing 25 of frame member F'. In this connection it will be understood that the gears 37 and g' are of the same size as the gears g on the shafts r', so that the shafts r' will be rotated to the same extent and at the same speed as the shaft 36.

As shown in Figs. 5 and 6 the arrangement of the gears I and I' is such that the driving gear I will rotate continuously while the driven gear I' will rotate intermittently and for a quarter of a revolution at each operation thereof. This is accomplished by providing eight teeth on the pinion I', four of which as at t, t, etc., are short teeth, and the alternating four remaining teeth t' are substantially longer than the teeth t.

The driving gear I is composed of two discs *i* and *i'* which are secured together by means of screws 39. The disc *i* has a single tooth recess 40 formed therein, while the disc *i'* has two teeth 41, 41 formed thereon so that the recess therebetween will register with the recess 40 in the disc *i*. The short teeth *t* of the pinion I' are adapted to be engaged by the teeth 41 on the disc *i'*, while the long teeth *t'* on said member I' are adapted to overlie the periphery of the disc *i*, as shown in Fig. 5. Thus, in the position shown in Fig. 5 the pinion I' is held against rotation by the engagement 15 of the sides of the pair of teeth *t'*, which rest against the curved periphery of the disc *i*, but when the rotation of the member I has progressed so that the nearest of the teeth 41 in the disc *i'* will engage a 20 tooth *t* on the pinion I', the recess 40 in the disc *i* will have attained a position beneath the left hand long tooth *t'*, as shown in Fig. 5, so that said tooth will fall into said recess and permit the rotation of the pinion I' for one quarter of a revolution, after 25 which said pinion will be again locked against rotation until another complete revolution of the driving member I has been effected. Thus, power from the motor M 30 being communicated through the driving mechanism hereinbefore described and the intermittent gears I and I' and the train of gears carried on the frame F, the longitudinal shafts *r*, *r*, etc., will be rotated for one quarter of a revolution at each revolution of the member I, for purposes hereinafter described.

The worm gear shaft D' of the driving mechanism carries on its upper end, above 40 the gear housing member h, a fly wheel A which has a bearing member a, pivotally carried on the upper side of the rim thereof on a pin 42. The reciprocable hollow shaft S which is centrally and horizontally 45 positioned in the machine is fixed at its rear end in a bearing 43 of a transverse yoke member Y by means of a set screw 44, or otherwise. The bearing member a is substantially elongated and slidably engages a transverse elongated slot 44 formed in the yoke Y. Thus, as the fly wheel A is rotated by the means hereinbefore described, the bearing member a will traverse the slot 44 of the yoke Y in alternate directions and will 50 effect the reciprocation of the hollow shaft S, thus determining the length of the stroke of said shaft.

Now, as shown in the drawings, particularly in Figs. 10 to 13 inclusive and in Fig. 60 2, I have provided six groups of brushes so arranged that all portions of a shoe will be engaged by the brushes during the operation of the machine for accomplishing the objects hereinbefore set forth. These 65 brush sets include a pair of groups B, B,

shown in Fig. 2 on the outer sides of the spaced foot rests f, f, which are adapted to receive the shoes during the operation of the machine, also a pair of similar groups B', B' on the inner sides of said foot rests, 70 all of the brushes of all of said groups mentioned being mounted on vertical axes.

Figs. 10 and 11 particularly show enlarged detail views of each of the groups mentioned, and it will be observed by reference 75 thereto that each group as at B, for instance, includes two sets of brushes which are similar in all respects, and a pair of sets of similar brushes as at B'', B'' are provided upwardly of the groups B, B, and B', B' 80 and are mounted on horizontal axes for engagement with the toe and upper portion of the shoes.

Each set of brushes included in the groups B, B' and B'' includes a cylindrical body 85 45 with a cleaning brush b, a polish applying brush b', and a finishing or shining brush, or pad, b'' arranged in the order named and providing a neutral or open space between the brushes b and b'' in each case. 90 The brushes b and b' of each set are preferably of bristles, as shown, which are suitably mounted in the body portions 45, and the finishing pads b'' in each set are preferably formed of a felt base 46 with a strip 95 of fleece 47 overlying the felt 46.

Each of the brush sets is removably but rotatably held on a cylindrical carrier 48 which has a shaft 49 fixed thereto and is held in a bearing 50. The pair of brush sets forming each of the groups, as at B, are rotatably carried on brackets 51, 51 and said brackets are pivotally held on opposite sides 52, 52 of a reciprocable carrier E, which embraces a shaft *r'* and is guided for reciprocable movement on one of the rods *r* by means of a lug 53 which extends outwardly from the carrier and has a recess for receiving the rod *r*. The brackets 51, 51 100 are pivotally held on said carrier by means of screws 54 at the upper and lower portions thereof, and said brackets are yieldably held on the carrier by means of springs 55 which may be arranged as shown in Figs. 10 and 11 with the central portion of each spring extending inwardly around a pin 56 on the upper side of the carrier E, and thence coiled around the portions 57, 57 of brackets 51 with the end portions of said springs extended downwardly through the 105 webs 58 of the brackets.

Each of the carriers E,—there being one for each of the brush groups B, B',—is provided with a hollow shaft or sleeve J, 115 which is substantially elongated and is journaled near one extremity in the carrier E and so arranged that its inner end will project into a central recess 60 in said carrier, and a gear 61 is mounted thereon within 120 said recess. 130

The hollow shaft J is adapted to be keyed or otherwise secured to the shaft r' in each case, for rotation therewith, by means of a key k , the arrangement being such that the shaft J will rotate with and reciprocate on the shaft r' . Motion is communicated to the shaft 49 of each brush set in the following manner: A transverse shaft 62 is provided in the carrier E, on which is mounted a gear 63 which meshes with and is driven by the gear 61 on the shaft J. Each of the brackets 51 carries a shaft 64 which is journaled in a bearing 65 formed on said bracket and is connected at 66 by means of a universal joint 15 with the shaft 62 of gear 63. The outer end of each of the shafts 64 carries a bevel gear 67 which meshes with and drives a bevel gear 68 on the lower end of the brush shaft 49. Thus, the arrangement is such that each of the brush sets may yield independently of the other in each group, and in the rotation of the shaft r' motion will be communicated to the shafts 49 of each brush set so that each brush set will be rotated to an extent corresponding to the rotation of the intermittent control gears I and I', namely, one quarter revolution at each operation, for bringing the brushes b , b' and b'' successively into operative position.

As shown in Figs. 2, 7 and 8, the front end of the hollow shaft S is fixedly held in a central bearing 70 formed on a cross head K which is transversely disposed in the machine and is guided on the guide rods r , r , etc., by means of guide portions 71, 71, etc., partially embracing said rods. Also, bearings 72, 72, etc., are provided in said cross head for embracing the intermittently rotatable shafts r' , etc., in which bearings the ends of the hollow driving shafts J, J, etc., are rotatably held. This structure is clearly shown in Fig. 8.

Motion is communicated to the brush sets B'' , B'' on each side of the machine in the following manner. The cross head K is provided with housing portions 73, 73 in the recesses 74 of which are mounted a pair of meter gears 75 and 76, the gear 75 in each case being connected for rotation with the inner end of the shaft J, and the gear 76 in each case being fixed to a vertical shaft 77 which is journaled in bearings 78 and 79 formed on vertical extensions 80 extended upwardly from the cross head K. Horizontal shafts 81, 81 are provided in bearings 82, 82 formed on the upper extremities of the extensions 80 from the cross head K, and the shafts 81 are adapted to be operatively connected with the vertical shafts 77 by means of bevel gears 83 and 84 which are, respectively, fixed to said shafts.

The brush sets B'' in each case are yieldably mounted on brackets 85 which are attached at their lower portions 86 to the cross head K and are extended upwardly and pro-

vided with bearings 87 to which arms 88 are pivotally connected by means of a pin or shaft 89 in each case. The inner portions of the arms 88 have bearings 90 which rotatably receive the brush shafts 49 and the shaft 49 is universally connected with the shaft 81 in each case by means of a universal joint 91 for imparting rotary motion to the brush sets B'' , regardless of the elevation of said brush sets.

The cross head K is fixedly held on the hollow shaft S by means of a set screw 92 or otherwise, so that when the machine is in operation said cross head will be reciprocated with the hollow shaft S.

From the foregoing description it will be observed that all of the brush sets B , B' and B'' are connected for reciprocation with the cross head K on shaft S, and said sets are also connected for rotation with the shafts r' , while said shafts r' are in turn connected with the driving mechanism through the interposition of the intermittent driving gears I and I'. The brush groups B and B' thus move in a horizontal path on opposite sides of the foot rests f which are supported on the bed plate P by means of suitable standards 94, and said brush sets are yieldable so that they will traverse the sides of the shoe from a common central position so as to cover all of the surface of the shoe at the sides.

The brush sets B' are arranged to traverse the upper portion of the shoe, and said brushes may be so formed by curving the peripheries thereof if necessary, in order that the entire surface of the shoe will be covered by one or the other of the brush sets.

Now, as hereinbefore stated, there are three separate operations to be performed in the shining of a shoe, namely, cleaning, which is necessarily the first operation, applying the polish after the cleaning has been completed, and finally shining or finishing the shoe, and it is necessary that separate brushes or elements be employed for each of these operations, therefore, in order to adequately provide for a sufficient number of strokes in each operation the timing of the driving mechanism shown in Figs. 3 and 4 is such that the number of reciprocations per minute of the cross head K and shaft S, together with the brushes mounted thereon will approximate 120 per minute for obtaining the best results. This will provide 30 strokes for each of the operations named, and 30 strokes while the brushes are in neutral position.

In other words, there are four cycles in each operation, three operating cycles and one neutral cycle. The changing of the brushes at the end of each cycle is effected by the intermittent gears I and I' hereinbefore described, but in order to effect the quick starting and stopping of the machine at the

beginning and end of a complete operation, and in order to effect the application of polish to the brushes b' in each set at the proper time and for a proper interval of time or 5 times, I provide a control mechanism shown clearly in Fig. 7, which includes a substantially large disc L mounted on a vertical shaft 95 which is journaled in a bearing 96 formed on the bed plate P, and is positioned 10 centrally between the frame members F and F' and beneath the hollow shaft S.

This shaft 95 also carries a ratchet N which is fixed thereto and has a plurality of teeth on the periphery thereof which correspond in number to the number of reciprocations per minute of the shaft S, namely, 120 as stated. The upper end of shaft 95 carries an arm 97 and a pawl 98 is pivotally held on the portion 99 of said arm for 20 engagement with the teeth of the ratchet N, whereby the rotation of said ratchet and the disc L may be effected for 1/120th of a revolution at each reciprocation of the shaft S.

25 Said arm 97 has an upwardly and rearwardly extended yoke 100 formed thereon which underlies the shaft S and has an elongated slot 101 therein adapted to be engaged by a pin 102 depending from a sleeve 103 fixedly held on the shaft S, as shown in Figs. 7 and 7^a. Thus, as the shaft S is reciprocated the pin 102 will enter the slot 101 on the rearward stroke thereof; and the slot being on a slight angle yoke 100 and the arm 97 will be moved to an extent sufficient to rotate the ratchet N for 1/120th of a revolution. The ratchet is prevented from reverse operation by means of a detent 103' which is suitably mounted on an arm 104 formed on a standard 194 attached to the base.

The drive shaft D connected with the motor M is also connected with an air compressor O by means of one of the couplings C, 45 and a tank T is provided on the bed plate P which has a major compartment 106 therein adapted to receive and hold a quantity of polish in liquid form, and a minor compartment 107 for receiving and holding air under pressure from the compressor O. Said compressor has an air inlet 108 and an outlet 109 which is suitably connected with the compartment 107, so that during the operation of the machine air will be continuously 50 compressed and delivered to the air storage compartment 107 for use in spraying the polish on the brushes, as hereinbefore described.

55 The polish compartment 106 of tank T has an outlet 109' which is connected with a T 110 from which pipes 111 and 112 lead to opposite ends of the machine adjacent the outer sides of the frame members F and F', said pipes being closed at their ends by 60 means of suitable fittings 113. The air stor-

age compartment 107 has an outlet 114 which is connected with a small pipe 115 having branches 116 and 117 leading transversely of the machine on the inner sides of the frame members F and F' respectively, to and 70 adapted for connection with the valves V, V' which are clearly shown in Figs. 20 and 21. From said valves pipes 118 are extended with branches 119 and 120 extended outwardly through the frames F and F' respectively, and thence transversely from the center of the machine into the longitudinal planes of the foot rests f.

The pipes 111 and 112 are provided with vertically extended tubes 121 in planes intermediate the brush sets B and B' on the outer sides of the frames F and F', as shown in Fig. 2 and in detail in Fig. 19. Said vertical tubes have spray nozzles 122 on their upper ends and the interior thereof in each case communicates with the interior of the pipes 111 or 112 so that the liquid from the compartment 106 may fill the pipes 111 and 112 and rise in the tubes 121 to a common level with that in the compartment 106 of 80 the tank.

The compressed air pipes 119 and 120 also have vertically extended tubes 120' with elbows 123 on their upper ends and horizontally disposed discharge nozzles 124, the tips of which overlie the tips of the nozzles 122 on the pipes 121, so that when the air is discharged from the nozzles 124 over the small orifice 125 a sufficient suction will be created in the pipes 121 to effect a discharge of the liquid from the nozzles 122, and the force of the air from the nozzles 124 will spray the liquid on the brushes b', b' of the groups B and B' in the same operation and also onto the same brushes of the sets B''.

It will be understood in this connection that it is only necessary to apply the polish to the brushes for a short interval of time and the spraying of the polish is effected and controlled by the operation of the disc L in the following manner. The valves V are of a type known as whistle valves and are fixedly held on the bed plate P of the machine on a longitudinal line cutting the axis of the disc L, there being two of said valves connected respectively with the pipes 116 and 117. Said valves have plungers 126 adapted to be engaged and operated by a lever 127 which is pivoted at 128 on the valve body and is extended substantially therefrom, as shown in Fig. 21. The disc L is provided with a pair of cams 129 and 130 which are substantially similar, and one of said cams 129 as shown, is attached to the lower side of the member L, while the member 130 is attached to the upper side thereof so that they will operate in different planes.

Said cams are held on the disc L by means of screws 131 or otherwise, and have peripheral portions 132 which overlie the edge of 130

the member L and are adapted for engagement with the valve operating members V' pivotally held on the bed plate P by means of screws 133 and having cam engaging rollers 134 carried on the arms 135 thereof. The members V' have substantially longer arms 136 with vertically formed and substantially elongated portions 137 formed thereon. The portions 137 of the members V' are bored at 138 to receive plungers 139, and are counter-bored at 140 for a suitable distance to receive the heads 141 on said plungers.

A spring 142 is carried on the stem 139 of each plunger within the counter-bore 140 and is adapted to compress between the bottom of the counter-bore and the lower side of the head 141 for normally urging the plunger upwardly. The counter-bore 140 of the portion 137 is closed at its upper end by means of a member 143 which is threaded or otherwise secured therein, and the plunger 139 has a reduced upper portion 144 which is slidably held in the closure 143 and projects upwardly therefrom.

The bearing 71 of the cross head K carries a bar 145 which is longitudinally disposed relative to the cross head and is adapted for engagement with the portion 144 of plunger 139 when the mechanism is in valve opening position. Likewise, the sleeve 103 carries a similar but reversely positioned blade 145' which cooperates with the rearmost member V' for engagement with the portion 144 of the plunger.

With reference particularly to Fig. 20 it will be observed that when the valve is closed the position of the member V' in each case is such that the end 144 of the plunger will be on one or the other sides of a longitudinal central plane of the machine which cuts the axis of the hollow shaft S, so that during the reciprocation of the brushes the bars 145 and 145' will move in a different plane than the plungers and therefore will not be effective for opening the valve. At the proper time, however, when the members V' are operated by the cams 129 or 130 as the case may be, the members V' will be moved so that the plungers 139 will be held in the path of the bars 145 and 145'.

Thus, at the proper time for applying the polish to the brushes, when said brushes have attained a position near the frame F at one end of the stroke of shaft S, the cam 129, for instance, will be effective for operating the member V' and the bar 145 will be effective for depressing the plunger 139 against the tension of the spring 142 so that the lower end of said plunger will overlie and depress the valve operating lever 127, and the movement of said lever will correspondingly depress the valve plunger 126 and serve to open said valve so that compressed air may be discharged from the pipe

120' through the nozzle 124 for spraying polish on the brushes. Likewise, at the other extreme of action the other member V' and its valve V will be correspondingly operated by the bar 145'. The polish may be similarly sprayed on the brushes at desired intervals by enlarging the peripheral portions 132 of the cams 129 and 130 or by multiplying such portions and arranging them at desired intervals on the periphery of the control disc L.

The starting of the machine is accomplished by dropping a coin through a slot 150 in a plate 151 mounted on the upper portion 6 of the outer housing H, said slot 80 being in communication with a flat tube 152 which extends downwardly on the interior of the housing H to a point opposite one end of the frame member F', and by the operation of a starting plunger 153 having 85 a knob or button 154 on the top thereof. Said plunger 153 may be guided in its movement by one or more bearings 155 attached to the side of the housing H, and it is adapted to be normally held upwardly by means 90 of a spring 156 interposed between a collar 157 on the plunger and one of the bearings 155, as shown in Fig. 7.

The lower end of the coin receiving tube 152 is open at its upper edge to receive a flattened portion 158 on the lower end of plunger 153, so that a coin, as at 159, when dropped into the tube 152 will lodge at the lowermost end of said tube beneath the flattened portion 158 of said plunger. Said coin is adapted to be held in such position by means of a bell crank 160 which is pivoted at 160' on the frame member F' and has an arm 161 projecting rearwardly from its axis, with a recess 162 formed in the outer end thereof and underlying the open end of the tube 152 and the flattened end 158 of said plunger. Thus, the coin 159 is adapted to lodge in the recess 162 of said arm so that when the plunger 153 is depressed the flattened portion 158 thereof will engage the curved edge of the coin, and the interposition of the coin between the plunger and the arm 161 when the plunger is depressed will effect the movement of the bell crank 160.

The bottom of the recess 162 in the arm 161, and the lower end of the plunger 153 are so formed that the coin will be discharged from the recess 162 and the tube 152 into a coin receiving box 163 when the plunger is moved to a maximum extent. Thereafter the plunger 153 and the bell crank 160 will be restored to normal position by the tension of the spring 156.

The bell crank 160 is operatively connected with a suitable switch which in turn is connected in the circuit of the motor M so as to energize the motor when a coin is deposited in the box 163. This switch includes a box 164 adapted to be suitably mounted

on the bed plate P on a transverse line cutting the axis of the control disc L. The switch proper includes an insulated collar 165 with a metallic ring 166 mounted on one side thereof, and having a plurality of contacts, four in number, for the character of device shown and described, as at 167, 167, etc., which overlie the periphery of the insulated collar 165.

10 Said switch is housed within the box 164 and is adapted to be enclosed by means of a suitable cover 168. The insulated collar 165 of the switch is carried on a hollow shaft 169 which is journaled in a bearing 170 on one side of the box 164 and embraces an elongated shaft 170 which is additionally journaled in a bearing 171 on the box. The hollow shaft 169 extends outwardly at one end from the box and carries a ratchet 172 having eight teeth formed on the periphery thereof and held on the shaft 169 by means of a set screw 173, or otherwise. The number of teeth in said ratchet equals twice the number of contacts 167, on the shaft as shown.

The shaft 170 is extended from the ratchet 172 and carries a bell crank 174 thereon which has an arm 157 operatively connected with the arm 176 of bell crank 160 by means of an elongated bar 177, said bar being connected respectively with the arms 175 and 176 by means of screws 178 and 179. The screw 179 operates in an elongated slot 179' formed in the bar 177 so that the operation 25 of the bell crank 160 will effect the operation of the switch in the box 164 for starting the machine, but when the said switch is operated for stopping the machine as hereinafter described, such operation will not effect the movement of the bell crank 160.

Bell crank 174 also has an arm 180 which carries a pawl 181 on a pivot screw 182 for engagement with the ratchet 172. Said ratchet is held against reverse operation by means of a detent 175' which is pivoted at 45 176 on the side of the box 164. Said detent is resiliently held in engagement with the ratchet by means of a spring 183 and the pawl 181 is resiliently held in engagement 50 with said ratchet by means of a spring 184. The switch box 164 has a pair of terminals 185, 185, which are in the form of screws, with pairs of nuts 186, 186 thereon. Said screws extend through insulating blocks 187, 187 attached to the inner sides of the box 164 by means of screws 188, 188, etc.

The terminals 185, 185 are extended through and have their heads overlying contact plates 189, 189 which have contact 60 points 190, 190 on their upper ends for engagement with the contacts 167 on the switch member 165. Thus, when the machine is in operation the contacts 190, 190 will engage the insulated segments intermediate the contacts 167, 167 and no current will flow

through the motor M, but when the coin 159 is dropped in the tube 152 and the plunger 153 is operated the bell crank 160 will be operated and serves to effect a corresponding operation of the bell crank 174, thus causing 70 the switch to be rotated one eighth of a revolution for moving a pair of the contacts 167 into engagement with the fixed contacts 190, thus completing the circuit of the motor M and serving to render the machine opera- 75 tive.

As hereinbefore stated, after a predetermined number of reciprocations of the brushes it is necessary to stop the machine and it is preferable that the machine be 80 stopped when the brushes have returned to neutral position, so as to provide ample space between the sets of brushes whereby the shoes may be positioned on the foot rests f, f, for a succeeding operation. This stopping operation is effected through the medium of the control disc L on the upper side of which is provided a stopping lug 191 adapted to engage an arm 192 which is fixedly held on the inner end of a starting and 85 stopping shaft 170.

The inner portion of said shaft 170 is journaled in a bearing 193 formed on a suitable bracket or standard 194 attached to the bed plate P, and the arrangement of this 95 stopping mechanism is such that the arm 192 will overlie the outer portion of the disc L in the path of the member 191, so that when the ratchet N has been operated for the 120th time the movement of the member 191 100 will be sufficient to effect the rotation of the shaft 170 for one eighth of a revolution so as to bring the insulated segments of the switch into engagement with the contacts 190 and to disengage the contacts 167 therefrom. 105

The bell cranks 160 and 174 of the starting and stopping mechanism, and their connecting bar 177 are normally held in the position shown in Fig. 14 by means of a spring 110 195 which may be attached at one end to the pawl pivot pin 182 on bell crank 184, and its other end to a pin 196 from the side of the housing 164. Thus, when the plunger 153 is operated for starting the machine, said bell cranks and said bar will be operated against the tension of said spring and upon the restoration of said plunger the bell cranks will be automatically restored to normal position. The same condition obtains 115 when said bell cranks and said bar are operated for stopping the machine by means of the control disc L and shaft 170.

Now, in operation it will be understood that the brush sets B and B' which are 120 mounted on vertical axes are oppositely positioned transversely of the machine, and are arranged in pairs, as shown in Fig. 2, on opposite sides of the longitudinal center line of the foot rests f. The brush sets B'' are 130

centrally mounted on horizontal axes in planes intermediate the groups B and B', in each case.

Said brushes are also arranged so that the 5 opposite brushes will normally be in close proximity and they are so disposed relative to the foot rests f that the rearmost brush sets will advance forwardly to a position 10 slightly in front of the toe of a shoe, and on the return stroke so that the foremost brushes will be positioned slightly behind the heel of a shoe. The brushes are guided in their movement over the sides of the shoe 15 solely by the shoes, and not otherwise.

15 The brush sets B'' are sufficiently forward of the brush sets B and B' in each case that when the cross head K attains its rearmost extreme of movement the brush sets B'' will advance sufficiently over the upper portion 20 of the shoe to clean, polish and shine the same, but not far enough to interfere with the foot or ankle of the person employing the machine for shining shoes.

It will be further understood that the 25 guide rods r, four in number, and the brush operating shafts r', also four in number, are parallel with the central guide rod R.

The polish applying mechanism shown and described is so arranged that the polish 30 will be applied simultaneously to all of the brushes b' on the sets B'', and the foremost brushes b' of the groups B and B' when the cross head K is substantially at its forward limit of action. Likewise the polish will be 35 applied to the brushes b' of the groups B and B' when said cross head is substantially at its rearmost limit of action.

At the beginning of an operation the person using the machine will be seated on the 40 seat 5 in such position that his shoes will rest upon a pair of rests f, f, which are centrally positioned with respect to and under the openings 8, 8. Thereafter when a coin is deposited in the slot 150 and the plunger 45 153 is depressed, the operation of the machine will be started in the manner hereinbefore described. At the beginning of each operation all of the brush sets are in neutral position, so that ample space will be provided 50 in the vicinity of the foot rests f whereby the shoes may be placed thereon preparatory to a shining operation. Ample time is allowed for the proper positioning of the shoes on said rests, due to the fact that 55 the neutral positions are provided on the brushes, and the initial cycle of the four cycles of each operation provides for approximately thirty strokes of the cross head K, and said brushes, before the brushes are 60 operated for positioning the brushes preparatory to a cleaning operation.

The fly wheel A and the driving mechanism shown in Figs. 3 and 4 are continuously operated subsequent to the operation of

plunger 153 for effecting the continuous reciprocal motion of cross head K and all of the brushes. At each operation of said cross head the control disc L is rotated for 1/120th of a revolution by means of the ratchet N and associated mechanism. On the 31st 70 stroke of the cross head the intermittent driving member I which is continuously rotated effects the rotation of shaft 36 and the driving pinion I', and motion is communicated therefrom through the gear g' 75 and the gears g, g, etc., of the frame F' and associated gears to all of the rods r. The rotation of the rods r' correspondingly effects the rotation of the brushes for one quarter of a revolution, so as to bring all 80 of the brushes b, b, etc., into operative position.

In a similar manner the brushes are successively moved at regularly timed intervals for bringing the brushes b' and b'' into operative position for effecting the polishing and shining operations, and upon the completion of the final cycle of each operation the brushes are again moved into neutral position preparatory to a succeeding operation of the machine. Immediately, however, upon the completion of the fourth cycle of the restoration of the brushes to neutral position, the lug 191 on the control disc L by means of its engagement with the arm 192 95 on switch shaft 170 effects the operation of the switch for stopping the machine.

During the second cycle of operation the valves V are operated by the cooperation of control disc L and the valve operating members V' for effectively spraying the polish onto the brushes at regularly timed intervals, and the continued reciprocation of the brushes over the shoe serves to effectively spread the polish over the shoe preparatory 100 to the finishing operation, which is effected by means of the brushes b''.

It will be also understood from the description and drawings of my improved machine that the intermittent driving members I and I' serve to lock the brush operating shafts r' and the brushes connected therewith against rotary movement, except when it is necessary to rotate the brushes and the shafts for changing the brushes in successive 115 cycles of operation. Thus the reciprocating movement of the brushes with respect to the shoes does not tend to rotate the brushes due to the friction between the same and the shoes.

Thus, it will be observed that I have provided a comprehensive machine completely automatic in operation, which is coin controlled for initiating the operation of the machine and is capable of being operated by 125 the deposit of a coin therein, and automatically stopped upon the completion of each operation. Also, the arrangement of the

mechanism is such that large or small shoes may be shined without any adjustment to the mechanism.

What I claim is:

- 5 1. A shoe shining machine including a motor, a continuously operated driving mechanism connected therewith, a carriage including a plurality of sets of brushes for successively cleaning, polishing and shining
- 10 shoes operatively connected with said driving mechanism and adapted to be continuously reciprocated, an intermittently operated driven mechanism operatively connected with said driving mechanism and with
- 15 said brushes for rotating said brushes for a fraction of a revolution at regularly timed intervals, and means connecting said driving and driven mechanism for normally locking said brushes against rotation for sustained
- 20 intervals and unlocking and rotating the same for short intervals, for the purpose described.
- 25 2. In a machine of the character described a pair of fixed frame members, a pair of parallel shafts rotatably mounted thereon, a cross head reciprocably mounted on said shafts, means for reciprocating said cross head, brackets reciprocably mounted on said shafts, a set of brushes yieldably mounted
- 30 on each of said brackets in opposed relation, means for rotatably connecting said brushes with said shafts, means for rotating said shafts at regularly timed intervals, and means operatively connected with said shafts
- 35 for locking the same against rotation for sustained intervals and for permitting the rotation thereof, as described.
- 40 3. In a machine of the character described a pair of fixed frame members, a pair of parallel shafts rotatably mounted thereon, a cross head reciprocably mounted on said shafts, means for reciprocating said cross head, brackets reciprocably mounted on said shafts, a set of brushes yieldably mounted
- 45 on each of said brackets in opposed relation, means for rotatably connecting said brushes with said shafts, means for rotating said shafts at regularly timed intervals, means operatively connected with said shafts
- 50 for locking the same against rotation for sustained intervals and for permitting the rotation thereof, and an auxiliary set of brushes supported on said cross head and operatively connected with one of said shafts
- 55 for rotation simultaneously with said other brushes.
4. A shoe shining machine including a plurality of independently yieldable sets of brushes for engagement with the sides of a shoe, said sets being arranged in opposed pairs and including separate brushes for cleaning, polishing and shining a shoe, and a set of similar brushes mounted at right angles thereto for engagement with the upper portion of a shoe, means for simultaneously reciprocating all of said brush sets to the same extent, means for intermittently rotating said brushes for operatively positioning the corresponding brushes of all of said sets for operative engagement with a shoe, successively, at predetermined intervals, and means for locking said brushes against rotation for sustained periods of time during reciprocation thereof, and for permitting and effecting the fraction of a rotation thereof for changing the brushes, as described.

FRANK H. NEWTON.
